UNITED STATES PATENT OFFICE.

ALBERT L. BARON, OF BROOKLYN, NEW YORK, ASSIGNOR TO CENTRAL LIGHTING COMPANY, OF NEW YORK, N. Y., A CORPORATION OF NEW JERSEY.

DESIGN FOR A LAMP-BODY.

SPECIFICATION forming part of Design No. 36,110, dated October 14, 1902.

Application filed May 7, 1902. Serial No. 106,376. Term of patent 14 years.

To all whom it may concern:

Be it known that I, ALBERT L. BARON, a citizen of the United States, and a resident of the borough of Brooklyn, county of Kings, city 5 and State of New York, have invented a new, original, and ornamental Design for a Lamp-Body, of which the following is a specification.

The leading feature of my design consists in a lamp-body having the particular shape and 10 ornamentation shown in the accompanying drawing, which is an elevation of a lamp-body exhibiting my new design.

The lamp-body has a concavo-convex cap with an outline of ogee shape. Beneath this 15 cap is a collar or disk with a series of spear-shaped heads or projections depending therefrom. Below this there follow between two concave rings a series of convex beads, some

narrow and some wide, as shown. Below the lower of these two concave rings is another 20 concave ring of greater diameter. Then follow two cylindrical rings of different diameters, the upper one having a series of screws projecting therefrom. Below the lower ring is a convex bead, and below this again is a 25 concave ring superimposed on a cylindrical ring, from which cylindrical ring a series of screws projects.

What I claim as new, and desire to secure by Letters Patent, is—
The ornamental design for a lamp-body substantially as shown and described.

ALBERT L. BARON.
